UNITED STATES PATENT OFFICE.

RUSSEL G. WOODWARD, OF WAUKEGAN, ILLINOIS, ASSIGNOR TO UNION SPECIAL SEWING MACHINE COMPANY, OF CHICAGO, ILLINOIS, A CORPORATION OF ILLINOIS.

OVERSEAMING SEWING MECHANISM AND PULL-OFF DEVICE THEREFOR.

No. 909,838.

Specification of Letters Patent.

Patented Jan. 12, 1909.

Application filed February 18, 1902. Serial No. 94,599.

To all whom it may concern:

Be it known that I, RUSSEL G. WOODWARD, a citizen of the United States, residing at Waukegan, in the county of Lake, State of Illinois, have invented certain new and useful Improvements in Overseaming Sewing Mechanism and Pull-Off Devices Therefor, of which the following is a description, reference being had to the accompanying drawing, and to the letters and figures of reference marked thereon.

The present invention relates to an improvement in overseaming sewing machines, particularly to machines of that type embodying, a thread-carrying looper, a spreader, and a reciprocating needle, the parts co-operating to form over-edge stitches for binding or ornamenting the edges of fabrics.

The present invention is an improvement or development of certain features illustrated in the Patent #837,106, granted to Lansing Onderdonk and myself November 27th, 1906.

The improvement herein shown and described has special reference to the mechanism for pulling off, and controlling the needle threads in the machine illustrated in the above mentioned patent, but, of course, may be applicable to other types of machines, and I, therefore, do not wish to be limited exclusively to a machine of the exact type shown.

My invention consists in the matters hereinafter described and referred to in the appended claims.

In the accompanying drawings which illustrate the invention, Figure 1 is a front view of the Union Special interlock machine, embodying my invention; Fig. 2 is a similar view with the bed plate and most of the mechanism broken away, leaving only sufficient of the mechanism to enable a clear understanding of my improvements; Fig. 3 is a top plan view partly in section, of Fig. 2; Fig. 3^a is a detail of the pull-off; Fig. 4 is a detail view showing the position of the parts of the stitch-forming mechanism as the spreader is about to release the needle loop; Fig. 5 is a detail view with the needle lever in section showing the nipper spring; Fig. 6 is a detail side view of the needle thread pick-up; Fig. 7 is a detail side eleva-

tion, partly in section, of the mechanism for adjusting the looper thread eyelets; and Fig. 7^a is a detail of the connection between the eyelets and the adjusting rod.

It is not necessary herein to refer, except in a general way, to the various elements of the machine, other than those which form the features of the present invention. It will be sufficient to refer for a more detailed description of those parts not herein specifically described and claimed, to the application hereinbefore referred to.

The shape of the machine is of the well known Union Special type, A being the bed plate, B the standard, C the gooseneck, D the needle lever, E the needle bar, F the needle bar carrier, and G the driving shaft.

N is the needle, L the looper and S the spreader or looping hook, the parts being so constructed and operating that the loop thrown out by the needle loop below the work plate is seized by the spreader or looping hook S and carried above the work plate to a point where the looper L in its oscillatory movement passes into it, and carries its own thread into position to be engaged by the needle in its next descent. The looper L is attached to an oscillating shaft M, and has suitably connected with its upper end so as to oscillate with it, an arm 100, having an eyelet 101, in its outer end. This movable arm is adjustably secured at its rear end through the slot 102 and screw 103, to the oscillating head 104, to which the looper-supporting shaft is attached. A pointer 105 secured at its rear end by screw 106, serves to indicate to the operator the amount of adjustment of the movable arm 100. This movable arm projects forward toward the front of the machine, into the path of the stationary eyelet 84, and the pivoted eyelet 85, which latter has a link connection with the needle bar carrier, but which, for the purposes of this invention, may be considered stationary. Another stationary eyelet 88 is provided on the upper portion of the needle bar gate.

As shown in Fig. 6, secured to the top of the needle bar and reciprocating with it, is what I have termed a needle thread pick-up, c. This is composed of two downwardly bent plates a, b, or one forked piece, and

having a spring *c'*, between the two. This friction device or pick-up *c*, is adapted in the downward movement of the needle bar, to engage and hold by friction, the thread 5 extending between the pivoted eyelet 85, and the eyelet 88. As the needle bar rises, the take up lightly engages the thread and carries the same up with the needle bar.

Intermediate the main pull-off and the 10 tensions *T*, I have placed an intermittent nipping device composed of two spring plates *d*, *e*, attached to a plate or clamp *f*, secured to the gooseneck of the machine, the needle thread passing between these 15 spring plates, and being alternately gripped and released by the spring plates under the action of a projection *g*, on the needle lever moving into and out of contact with one of the plates; the nipper springs being closed, 20 while the pick-up or friction device *c* is in operation, and open while the main pull-off is in action. A supplemental pull-off *Q* is provided between the nipping device and the tension *T*, and adapted to pull-off 25 thread for the use of the spreader, while the nipper springs are closed, giving up this thread to the spreader when they are opened. This supplemental pull-off may be of any suitable construction, but as here- 30 in shown, comprises a loop *h*, of wire attached to a collar or clamp on the needle lever, and a second wire *i*, on the gooseneck of the machine.

The operation of these parts may be 35 briefly described as follows: Assume the needle bar at lowest position and about to ascend, so that the needle may throw out a loop, the intermittent nipping device has been closed by the downward swing of the 40 forward end of the needle lever, thus no thread is being drawn from the spools, and that portion of the thread which extends between the needle bar lug eyelet and the left hand eyelet on the gooseneck, is en- 45 gaged by the friction clamp, or so-called pick-up device. As the needle bar rises, the pick-up device lightly holds the thread and carries the thread extending between the pick-up and the eye of the needle up with 50 the needle, and straightens out the kink which might be formed in throwing out the loop, and causes the loop to be properly thrown out and positioned to be engaged by the point of the spreader, but releases it 55 practically as soon as this engagement of spreader and needle loop takes place. Meanwhile, as above stated, the nipper spring is closed so that the supplemental pull-off between the nipper spring and ten- 60 sions is pulling off a slight quantity of thread from the spool, and by the time the spreader in its forward and upward move- 65 and further strain might break the thread

or draw on the seam, and curl or pucker the fabric, the needle lever has swung so far that the thread is released by the nipper springs, and the spreader without strain on the thread or material has enough thread 70 supplied to it to enable it to deliver the needle loop to the looper. As the needle bar reaches its highest point and begins to descend, the looper meanwhile having passed into the needle loop on the spreader, 75 the main pull-off acts by the swinging of the guiding arm carried by the looper past the pivoted eyelet on the left of the machine, to pull-off thread from the spools, until it reaches the limit of its swing to the left, at 80 which time the nipper springs have closed.

From the above statement of operation, the timing of the main pull off and the nipper springs will be apparent. The nipper springs are closed by the needle lever, which 85 operates the supplemental pull off. The looper of course, is operated in timing so as to move forward for the entrance of the needle into the looper thread loop. Therefore, the main pull off, which is carried by 90 the looper bar will move forward to pull thread during the forward movements of the looper, which take place on the very first part of the down stroke of the needle. It will therefore, be seen that I have pro- 95 vided means for causing the gripping de- 100 vice or nipper springs to release the thread, while the main pull off is acting to pull thread from the supply, and to grip the same, while the supplemental pull off is act- 105 ing.

In general, the looper thread pull-off is similar to that shown in the above entitled patent, as comprising the movable fingers or arms *7*, having shoulders *8*, extending be- 105 tween eyelets *9* on the frame of the machine, through which eyelets the looper thread is guided. In a plane between these fingers or arms is a pivoted cast-off plate *11*, which, at one time or another, according to its position, acts to force the thread off the shoulders *8*, on the movable fingers *7*.

As a further improvement in machines of this character, the pull-off for the looper thread is made adjustable by adjusting the arms *R*, carrying the eyelets *9*. These arms are formed on a common support *n*, which is adjusted back and forth by the screw-threaded rod *U*, having on one end the thumb piece *k* and screw-threaded through 115 a part of the gooseneck of the machine, and at its other end attached to the support for the arms *R*. This support fits in a depression on the gooseneck of the machine, being slotted at *x*, and having the external plate *y*, secured to the gooseneck by the screw *z*, which passes through the slot, the plate *y*, having upper and lower flanges to embrace the upper and lower edges of the support *n*. By this arrangement, the operator may regu- 120 125 130

late the amount of looper thread required, when thickness of goods, or tightness of stitch varies, and this, too, can be done without stopping the machine, by merely turning the screw rod U.

It will be understood that this feature of the operators being able to regulate the amount of looper thread without stopping the machine is of great practical importance

10 in a machine of this character; for example, very frequently an operator will have a number of lots of goods brought to her of varying weight or thickness and by this arrangement she can run from one lot to another without stopping the machine and regulate the supply of thread for the looper to give the proper elasticity to the stitch by simply turning the screw rod U in one direction or other.

20 The mechanism for adjusting the looper thread pull-off, herein shown and described, is not claimed, as it forms the subject matter of the claims of an application filed by me on the 17th day of April, 1902, Serial No. 25 103,323, said application having been filed as a division of this one.

Having thus described my invention, what I claim as new, and desire to secure by Letters Patent, is:—

30 1. In an overseaming machine having stitch-forming mechanism including a needle, a pull-off device for drawing needle thread from the supply, an intermittently acting gripping device, and a supplemental pull-off acting upon the needle thread, the main pull-off being located between the needle and the intermittently acting gripping device, and means for operating the latter to cause it to release the thread while 40 the main pull-off is acting, and to grip the thread while the supplemental pull-off is acting; substantially as described.

2. In a sewing machine, a pull-off device for the needle thread, an intermittently acting gripping device therefor, constant tensions, and a supplemental pull-off located between the intermittently acting gripping device and the constant tensions, the main pull-off being located between the needle and the 50 intermittently acting gripping devices, with means for causing the gripping device to release the thread while the main pull-off is acting to pull thread from the supply and to grip the same while the supplemental pull-off is acting; substantially as described.

3. In a sewing machine, a main pull-off device for the needle thread, a reciprocating pick-up for engaging the needle thread in the upward movement of the needle and carrying the needle thread up with the needle, an intermittent gripping device with means for causing it to release the thread while the main pull-off is acting and to engage it when the friction device is acting and 60 a supplemental pull-off with means for caus-

ing it to pull off thread while the gripping device is holding the thread; substantially as described.

4. In a sewing machine having stitch forming mechanism including a needle and means for operating it, a looper co-operating therewith, a spreader or looping hook arranged to take a loop of needle thread and carry it into position to be engaged by the looper, a main needle thread pull-off, an intermittently acting gripping device, a supplemental pull-off and means for causing the gripping device to release the thread, while the main pull-off is acting, and to engage the thread while the supplemental pull-off is acting; said supplemental pull-off giving up thread to the spreader substantially as described.

5. In an overseaming machine, including a needle, a looper and a spreader arranged to take a loop of thread and carry it into position to be engaged by the needle in its descent, a plurality of pull-off devices acting upon the thread and an intermediately located intermittently acting gripping device for said thread; one of said pull-off devices giving up thread to the spreader substantially as described.

6. In a sewing machine having stitch-forming mechanism, including a needle and means for operating it, a thread carrying looper and means for operating it, a spreader or looping hook, arranged to take a loop of needle thread beneath the work plate and carry it into position to be engaged by the looper, a main needle thread pull-off, a friction device for engaging the needle thread in the upward movement of the needle, and carrying the needle thread up with the needle, tension devices, and an intermittent nipper spring with means for causing it to release the thread while the pull-off is acting, and to engage it when the friction device is acting; substantially as described.

7. In a sewing machine having stitch-forming mechanism, including a needle and means for operating it, a thread carrying looper and means for operating it, a spreader or looping hook, arranged to take a loop of needle thread beneath the work plate and carry it into position to be engaged by the looper, a main needle thread pull-off, a friction device for engaging the needle thread in the upward movement of the needle, and carrying the needle thread up with the needle tension devices, and an intermittent 115 nipper spring with means for causing it to release the thread while the pull-off is acting, and to engage it when the friction device is acting, and a supplemental pull-off 120 between the nipper spring, and the tension to supply slack thread for the spreader; substantially as described.

8. In a sewing machine, a pull-off device for the needle thread, a pick-up device for the same independent of the pull-off, an in- 130

- termittent gripping device for the thread, and a supplemental pull-off for the needle thread with means for operating said intermittent gripping device to cause it to release the thread while the main pull-off devices are operating, and for gripping the thread while the supplemental pull-off is acting; substantially as described.
9. In a sewing machine and in combination with the stitch forming device, an adjustable thread guiding arm and means for

reciprocating it and an indicating device or pointer mounted in a plane above said thread guiding arm and reciprocating with it to, indicate the amount of adjustment 15 thereof; substantially as described.

In testimony whereof I affix my signature, in presence of two witnesses.

RUSSEL G. WOODWARD.
